EXCAVATOR TOOTH

Ferrald Daniel Stephenson, 4562 Lomina, Lakewood, Calif., assignor of ten percent to Thomas C. Whisler, Sr., Alameda, Calif.

Filed Apr. 28, 1958, Ser. No. 731,215

11 Claims. (Cl. 37—142)

My invention relates to excavating machinery particularly machinery in which some sort of a digging member such as a blade or dipper bucket or the like is provided with serrations or teeth along the leading edge. Since the teeth are subject to considerable wear, it is customary to provide removable and replaceable teeth or tips for the teeth which can readily be detached in the field when worn and can as readily be replaced with new members. In some instances the replaceable parts are supported directly on the dipper bucket or other excavating devise referred to as a base, while in other instances the replaceable parts are supported directly upon an adapter which in turn is supported upon the base. In either instance, there exists a problem of providing a firm immovable support for the replaceable member when it is in operating condition and also of affording a construction so that the part can readily be removed when worn and as readily replaced with only ordinary field tools and field labor.

In use the forces which are exerted upon the tooth tip and through the tooth tip onto adapted or directly onto the base are of complex nature being imposed from various directions at different times during the digging operation. Various forces at various directions are also imposed depending upon the nature of the material being excavated. For discussion it can be considered that the base is moving in a horizontal direction and that the leading edge is moving from right to left and further, that the adapter (if used) and the tooth tip are arranged so that they project forwardly from the leading edge and are contoured so as to be principally disposed in the direction of advance of the edge. If then the tooth tip encounters resistance directly ahead, the resulting force on the tooth tip and ultimately the base is approximately in the general line of the structure and is well resisted. It is usual to provide a V-shaped inter-engagement between the tooth tip and the adapter or base so that a resulting force in the indicated direction tends to wedge the tooth tip even more tightly upon its supporting structure. This is for the reason that the point or apex of the V is directed forwardly. This arrangement provides for easy assembly and disassembly and generally is satisfactory so long as the majority of the forces are imposed in the indicated direction.

In much excavation, however, the tooth tip is moved in a direction having a major component transversely to the direction first discussed. That is, the point of the tooth tip is lifted, often with the maximum load being imposed near the extremity of the tooth tip. This imposes a large transverse downward force 2 (Figures 8 and 9) upon the tooth tip. If this vertically downward force is resolved in the usual fashion into two components one component 3 normal to the upper pair of substantially parallel inter-engaging surfaces of the V and the other component 4 along the upper pair of inter-engaging surfaces of the V it is apparent that the component 4 parallel to or along the upper pair of surfaces of the V is effective in a direction to cause loosening of the tooth

2

tip from its base. Considered in another way, the component 4 of the force parallel to or along the upper surface of the V is a force having a moment arm about an arbitrary central point P (Figure 8) within the base so that there is a tendency under these conditions to rotate (counterclockwise in Figure 8) or bend the tooth tip off of its support, a tendency which if productive of motion is often referred to as creeping. In practice, if creeping once starts and produces some wear it is rapidly progressive and the tooth tip becomes unsatisfactorily loose and quickly is useless.

It is therefore an object of the invention to provide an excavator tooth having a removable tip so related to its base as to resist satisfactorily not only the head-on forces but also the transverse or downward forces which otherwise tend to produce creeping.

Another object of the invention is to provide an excavator tooth having an improved inter-connection between the removable tooth and its supporting base.

20 A still further object of the invention is to provide an excavator tooth having means adapted to resist transverse and especially downwardly transverse forces.

A still further object of the invention is to provide an excavator tooth with a removable portion mounted in such a fashion as to resist rotational dislodging forces.

An additional object of the invention is to provide a removable excavator tooth having means for resisting dislodgment yet one which can be readily assembled and disassembled by the usual field tools and techniques.

30 An additional object of the invention is to provide an excavator tooth which is readily installed and, once installed, is firmly mounted so as to resist loosening and wear-producing motion throughout its operational life.

A still further object of the invention is in general to improve excavator teeth.

Other objects, together with the foregoing, are attained in the embodiment of the invention described in the accompanying description and illustrated in the accompanying drawings in which:

40 Figure 1 is a side elevation with broken away portions in cross section on a vertical longitudinal plane showing the excavator tooth in initial assembly position with respect to an adapter and base mounting;

Figure 2 is a view similar to Figure 1 but showing the parts in a partially assembled condition;

Figure 3 is a similar view, but showing the parts in fully assembled and operating condition;

Figure 4 is a plan, certain portions being broken away, of an excavator tooth on its base;

50 Figure 5 is a cross section the plane of which is indicated by the line 5—5 of Figure 3;

Figure 6 is a view like Figure 5 and showing a cross section the plane of which is indicated by the line 6—6 of Figure 3;

Figure 7 is a perspective view of a mounting.

Figures 8 and 9 are diagrams illustrative of one of the forces imposed upon the structure and its resolution into components.

60 While the excavator tooth of the invention can be and has been successfully incorporated in a number of variant forms it has been commercialized in the form shown herein. In this environment, there is provided a base including a dipper body 6 to which a removable adapter

65 7 has been applied. It is understood that in some instances the body 6 and the adapter 7 are separate entities whereas in other instances the body 6 and the adapter 7 are integral. In both instances they constitute a suitable base. In either instance it is considered, for purposes 70 of discussion, that the base including the member 7 is disposed so that an arbitrary center line 8 has a horizontal orientation and serves also to locate a horizontal plane

of symmetry. The base 7 includes an upper central surface 9 substantially planar and converging forwardly or toward the left in the figures in the direction of the central plane 8. Similarly and symmetrically arranged is a lower planar central surface 11 also converging toward the central plane 8.

At both sides of the structure, as shown in Figure 4, there are provided parallel upper surfaces 12 and 13 which are usually disposed at the extremities of lateral ribs 14 and 15. The surfaces 9, 12 and 13 near their ends curve toward the outer surface 16 at the top of the member 7. There are similar ribs 17 and 18 having surfaces 19 and 20 substantially parallel with the surface 11 and at their ends curving toward the nether surface 21 of the member 7. The surfaces 9 and 11 are dihedral surfaces for the most part defining a V-shaped inter-connection on the base 7. The surfaces 12, 13, 19 and 20 are other dihedral, planar converging surfaces also partially defining the V-shaped inter-connection on the base 7.

Adapted to be assembled with the base 7 is a tooth tip 22 being substantially rectangular in plan and having an upper surface 23 and a lower surface 24. These surfaces are substantially planar, are usually although not necessarily approximately parallel to the respective surfaces 9 and 11, and converge into a relatively sharp, linear point 25 at the leading edge of the tooth tip.

The interior of the tooth tip 22 is provided centrally with a surface 26 which is substantially planar and extends between lateral surfaces 27 and 28 which are approximately parallel thereto; the arrangement being such that when the tooth tip is assembled on the base the surfaces 27 and 28 substantially abut the surfaces 12 and 13, whereas the surface 26 may abut or may have some clearance with respect to the subjacent surface 9.

Since preferably the parts are substantially symmetrical about the center plane 8, the tooth tip 22 likewise has a central surface 31 adapted to be disposed opposite and perhaps in abutment with the nether surface 11 and also has a pair of approximately parallel side surfaces 32 and 33 which preferably contact in assembled condition the adjacent lower surfaces 19 and 20 of the body 7. While the various convergent surfaces forming the V inter-connection are for the most part in abutment, there is some variation possible in commercial practices and techniques so that not all of the surfaces need be in forced engagement in actual operation. If several of the surfaces are in reasonable abutment that is commercially satisfactory.

The tooth tip 22 thus is not only in firm engagement with the base 7 above and below, but also especially for heavy-duty installations, is provided with side walls 41 and 42 having outer planar faces 43 and 44 and also having interior surfaces 46 and 47 which are approximately parallel to and, often, in assembled condition abut the parallel side surfaces 48 and 49 of the base 7. There is in effect a hollow box tooth tip imposed upon a tooth base having a substantially rectangular cross section in order that forces from lateral and vertical directions can be resisted.

In order to hold the tooth tip firmly upon but readily removable from the base, the tooth tip itself is provided with a pair of central aligned openings 51 and 52 which are designed to be in approximate registry with a central, vertical aperture 54 extending through the base 7. A wedge 56 is received within the properly aligned openings 51 and 52 and the aperture 54 and when driven home urges the parts into firm engagement. Conveniently, there is a deformable rubber insert 57 in the substantially V-shaped wedge 56. The insert has a metal wear ring 58 embedded therein except for its exposure along the leading portion of the wedge, so that the ring can be seated in a corresponding depression 59 in the wall of the aperture 54 when the wedge is tightly engaged. When the wedge is in position, the parts are

firmly held under pressure because of the presence of the resilient rubber, yet when the wedge is driven out, the parts can easily be detached.

As so far described, the excavator tooth is typical of a relatively standard construction. Pursuant to the invention, the base 7 is not entirely symmetrical. In the leading portion of the base, whereas the surface 11 is continued directly to merge with the blunt forward surface 71, the upper surface 9 is not continued to converge symmetrically toward the forward surface 71. Rather, at a convenient point in its length, the surface 9 no longer converges. At a zone of inflection 72, the convergence of the surface 9 stops. At that zone there arises a new upper surface 73. This is central and planar like the surface 9 but instead of converging further toward the central plane 8, diverges forwardly and upwardly therefrom and from the plane 8, finally merging with the forward surface 71 at a point considerably higher or farther from the center than the zone 72. The planar surface 73 may or may not be parallel with the surface 11 and may or may not diverge upwardly from the inflection zone 72 at the same degree or rate as the surface 9 diverges therefrom in the opposite direction.

The important factor is that the upper surface 73 and the raised surface 71 afford an upstanding discontinuity or "toe" 74 characterized by an upstanding projection in the leading, upper portion of the base 7. The toe 74 is partly bounded by the surface 73 which is different in inclination, or is inclined in an opposite sense to the inclination of the surface 9. There is a greater thickness of metal beneath the surface 73 than there would be if the surface 9 were continued to the end of the base, as is usual. In this sense, there is a greater thickness of metal, as the surface 71 is approached, than there would be if the surface 9 continued to the surface 71.

While the present drawings are roughly to scale with present commercial embodiments, the precise angles illustrated are not essential or critical. The effect of the surface 73 can, however, be understood by again considering a vertically downward force 2 (Figure 9) resisted at the surface 73. If this vertically downward force is analyzed into its two components, as previously was done, one of the components 5 is parallel to the plane of the surface 73. The other component 1 is normal to the surface 73. While the normal component 1 has no effect other than to press the parts together, the component 5 parallel to the surface 73 has a direction tending to force the tooth tip 22 farther onto the base 7 or to drive the various inclined wedge surfaces more firmly into contact. As before, if the force 5 parallel to the surface 73 is considered as a force having a moment arm about some central point P in the toe 74, then the resulting rotational force (clockwise in Figure 9) is opposite to the dislodging or downward force and tends to oppose the creeping action originally defined. Thus by the provision of the upwardly extending toe 74, a substantially improved inter-connection between the tooth tip and the base is afforded.

So that the surface 73 is appropriately abutted within the tooth tip, the surface 26 although continuing parallel to the surface 9 for the most part, itself reaches a zone of inflection 77 marking the beginning of a surface 78 which is planar but diverges upwardly from the plane 8 and eventually rounds into a forward surface 79 approximately parallel to the surface 71. The surface 78 in part defines a forward portion of the hollow interior of the tooth tip. This forward portion is an enlargement as compared to the immediately adjacent part of the hollow interior, especially that portion thereof between the forward parts of the surfaces 26 and 31. The surfaces 73 and 78 are in abutment, even strongly compressive abutment, when the parts are appropriately assembled and particularly under the forces exerted during operation.

Since it is desired that the tooth tip 21 be reversed to increase its effective life after initial wear, the surface 31 also has a zone or line of inflection 81 which marks the beginning of a divergent planar surface 82 rounding at its forward portion into the surface 79. The surface 82, like the surface 78, partially defines an enlargement in the hollow interior of the tooth tip as compared to the relatively small volume defined between the forward portion of the surfaces 26 and 31. With this arrangement, when the wedge 56 has been removed and the tooth tip 22 driven forwardly and off of its base, the tooth tip can be rotated or inverted and repositioned. The surface 82 is then in tight abutment with the surface 73 and the wedge can then be reinstalled. In the inverted position the tooth tip is again supported by the toe 74 against the downwardly exerted dislodging forces and the creeping is also resisted.

In the assembly of the tooth tip onto the base 7 the parts move progressively substantially as shown in Figures 1, 2 and 3, the precise direction of motion of the tooth tip onto the base in the initial part of the assembly being immaterial. The motion is generally along the line of symmetry 8 whereas in the final part of the assembly there is usually, although not necessarily, a relative sliding movement of the surfaces 73 and 78 until the parts are in home position as illustrated in Figure 3. The particular angularities involved in the various surfaces and the clearances which are provided between some of them may change during manufacture (casting) and after use. They may be varied to accommodate manufacturing practices or particular requirements of an individual installation, but the general proportions and arrangements and angularities of the parts are conveniently made approximately as illustrated in the drawings.

If this arrangement is followed there is provided a removable excavator tooth which is firmly mounted when in position and which has especial resistance to forces tending to produce a creeping or rotary dislodgement of the tooth tip. The device is readily fabricated by the usual casting methods and is reversible as desired. It is easily assembled by the usual techniques and with the usual field tools and is as readily disassembled either for reversal or for replacement.

What is claimed is:

1. An excavator tooth comprising a base having a forward portion symmetrical about a horizontal plane and defined by side surfaces and by upper and lower planar surfaces converging forwardly toward said horizontal plane, and a toe on said base asymmetrically upstanding from said upper surface of said forward portion, said toe in part being defined by a single planar top tooth tip-engaging surface parallel to said lower surface and at its rear merging with said upper surface and at its front merging with a base surface substantially normal to said horizontal plane.

2. An excavator tooth comprising a base having a central plane of symmetry and partially defined by upper and lower planar central surfaces converging toward said plane of symmetry in a forward direction, a toe merging with and upstanding from one of said base central surfaces and having a planar face diverging from said base plane of symmetry in a forward direction, a tooth tip having a central plane of symmetry and partially defined by interior upper and lower planar central surfaces converging toward said plane of symmetry in a forward direction, said tip also having an interior planar face merging with and extending from one of said tip central surfaces and diverging from said tip plane of symmetry in a forward direction, and means for holding said base and said tooth tip in engagement with said central surfaces substantially in engagement and with only said diverging planar face of said toe in abutment with said interior planar face of said tooth tip.

3. An excavator tooth comprising a base having a transverse central plane and including substantially paral-

lel planar side surfaces, including a planar lower surface converging forwardly toward said central plane, including a planar upper surface converging forwardly toward said central plane, and including a toe upstanding from the forward portion of said upper surface and in part defined by a planar top surface parallel to said lower surface, and a tooth tip adapted to be assembled with said base and when so assembled including substantially parallel planar side walls substantially contacting said side surfaces, including a planar lower wall substantially contacting said lower surface, including a planar upper wall substantially contacting said upper surface, and including means defining a lower surface substantially contacting said top surface of said toe.

15. An excavator tooth comprising a base having a transverse central plane and including side surfaces, including upper and lower planar surfaces converging forwardly toward said plane, and including a toe upstanding from said upper surface in the forward portion thereof and in part defined by a planar top surface diverging forwardly away from said plane, and a tooth tip adapted to be assembled with said base and when so assembled including side walls substantially in abutment with said side surfaces, including planar upper and lower walls substantially in abutment with said upper and lower surfaces, and including an interior lower wall substantially in abutment with said top surface.

20. An excavator tooth base having a transverse central plane, said tooth base including side surfaces, including upper and lower planar surfaces converging forwardly toward said central plane, said tooth base terminating in a leading portion and having a toe upstanding farther and farther from said central plane at positions closer and closer to said leading edge and in part defined by a top 25 load receiving surface approximately parallel to said lower surface.

25. An excavator tooth comprising an interfitting base and tooth tip, said base having a transverse central plane of symmetry and including side surfaces and including upper and lower planar surfaces converging forwardly 30 toward a leading edge, said tooth tip including side walls in substantial abutment with said side surfaces, including upper and lower walls in substantial abutment with said upper and lower surfaces respectively, and interfitting means on said base and on said tooth tip defining abutting planar areas merging with said upper planar surface and said upper wall and diverging from said central plane in a direction to impose a force component in said plane and in a direction urging said tooth tip into tighter 35 abutment with said base when a downward force normal to said plane is exerted on said tooth tip.

30. An excavator tooth base comprising a wedge-shaped member having substantially parallel side surfaces and having planar upper and lower surfaces converging forwardly 40 toward a transverse plane of symmetry, said tooth base terminating in a leading portion, and means forming a toe upstanding from said member adjacent said leading portion, said toe having a planar top area which is the only area of said tooth base diverging forwardly away 45 from said plane of symmetry.

35. An excavator tooth tip comprising a hollow wedge-shaped member having substantially parallel side walls and having upper and lower walls converging forwardly 50 toward a transverse plane of symmetry, all of said walls defining a wedge-shaped cavity terminating at a forward surface, and means defining a nether planar area on said upper wall adjacent said forward surface which is the only area on said upper wall of said member diverging forwardly away from said plane of symmetry.

40. An excavator tooth comprising a V-shaped wedge face having a central plane of symmetry and having a relatively thin leading edge, a projection on said base and having a surface merging with one face of said wedge, said projection being thickest at its extreme leading portion relative to said plane of symmetry, a tooth tip hav-

ing four walls defining a V-shaped wedge hollow interior adapted to overlie said base and having a wall diverging forwardly from said plane of symmetry and overlying said projection, and means for holding said tooth tip on said base with said V-shaped wedge portions substantially in abutment and with said surface and said wall in abutment.

10. An excavator tooth comprising a wedge-shaped base having a transverse central plane of symmetry and including upper, lower and two side surfaces and a tooth tip having a wedge-shaped cavity adapted to envelop said base and abut said upper, lower and two side surfaces, and means including abutting planar portions on said base and on said tooth tip inclined relative to said central plane in a direction opposite to the direction of inclination of the upper surface of said wedge-shaped base relative to said central plane for imposing a force component urging said tooth tip into tighter abutment with said base when a downward force is exerted on said tooth tip.

11. An excavator tooth comprising a base having a transverse plane of symmetry and having the contour of a V-shaped wedge defined between an upper plane and a lower plane converging forwardly toward said plane of symmetry except for a central projection upstanding from said wedge above said upper plane, said projection having

5 an upper planar surface that is increasingly farther from said plane of symmetry when measured at increasingly forward positions, and a hollow tooth tip movable into assembled position with said base, the hollow in said tip having substantially the contour of said V-shaped wedge and having an interior surface substantially abutting said upper planar surface of said projection in said assembled position.
